HINGING-LOCKING MECHANISM

Albert Henry Franks Perl, Birmingham, England

Application March 29, 1934, Serial No. 717,957
In Great Britain March 28, 1933

2 Claims. (Cl. 16—146)

This invention relates to an improved hinging-locking mechanism for use on tables provided with folding legs, such as for example, card or picnic tables, and the invention consists in the hinging-locking mechanisms, and tables with folding legs, provided with such mechanisms, all as hereininafter described and claimed.

The invention is illustrated in the accompanying drawings in which

10 Figs. 1 and 2 show the hinging-locking mechanism according to the invention applied to connect a leg of a collapsible table, for instance, a card table, to the table top, Fig. 1 showing in full lines the leg folded close to the table top and in broken lines the leg opened to its vertical position, but prior to being locked in that position, and Fig. 2 shows the parts in the locked position.

15 In the drawings, the hinging-locking mechanism according to this invention comprises four hinge-plates P_1 , P_2 , P_3 and P_4 which are connected together by the four pintles H_1 , H_2 , H_3 and H_4 . The hinge-plate P_1 is bent to form four sides of an open rectangular box adapted to receive the top of the leg M when the latter is folded close to the table top T . The hinge-plate P_1 is rigidly fastened to the underside of the table top T and the hinge-plate P_3 is rigidly fastened to the leg M which may be positioned at the corner of the table, as shown. The hinge-plates P_1 and P_3 are connected together by the pintle H_2 . The hinge-plate P_3 is also connected to the hinge-plate P_4 by the pintle H_3 and the hinge-plate P_1 is also connected to the hinge-plate P_2 by the pintle H_1 . The hinge-plates P_2 and P_4 are connected together at their adjacent ends by the pintle H_4 . The pintles H_1 and H_3 are arranged in the same plane, and the pintles H_2 and H_4 are also arranged in the same plane, these two planes being at right angles to each other.

20 When the leg M is in its folded position, as shown in full lines in Fig. 1, the pintles H_2 and H_4 are collinear, thereby enabling the leg M to be moved away from its folded position into its operative position shown in broken lines in Fig. 1. In this position of the leg M , the pintles H_1 and H_3 are collinear, thereby enabling the hinge-plates P_2 and P_4 to rotate, as one member, about their respective pintles H_1 and H_3 into the position shown in Fig. 2, in which they prevent movement 25 of the leg M in any direction from its open position and thereby effectively lock it in that posi-

tion. The provision of a spring S surrounding the pintle H_3 renders this locking operation automatic.

One of the sides of the box member P_1 acts as a stop against which the locking hinge-plate P_2 abuts in the locking position of the hinge-plates P_2 and P_4 . In order to provide a still more rigid device, a projection 3 is provided on the hinge-plate P_2 which engages, in the locking position, in a slot 2 in the adjacent side wall of the hinge-plate P_1 . This engagement between the projection 3 and slot 2 ensure that any play which may be present in the hinges, due to inaccuracies arising out of mass production methods of manufacture, is effectively counteracted, and a rigid structure results.

I claim:—

1. In and for a table with folding leg, a hinging-locking mechanism comprising a hinge-plate for attachment to said leg, hinged to a second hinge-plate for attachment to said table, two further, locking, hinge-plates hinged together and also hinged to the first two hinge-plates aforesaid, one to each, the pintles which hingedly connect all said hinge-plates lying in two planes at right angles to each other so as to permit of relative movement between said first two hinge-plates into a predetermined position, whereat the pintles connecting said first two hinge-plates with said locking hinge-plates are collinear, to permit said locking hinge-plates to rotate about the pintles last-mentioned and thereby lock and brace said first two hinge-plates in said position, said second hinge-plate being bent to form a box, of which said hinge-plate constitutes one end, having the other end and the top open to accommodate said leg when folded, and adapted to be secured by its bottom to said table, one side of said box forming an abutment adapted to be engaged by the adjacent one of said locking hinge-plates in the predetermined position aforesaid, and a spring for urging said locking hinge-plates into their locking position.

2. In and for a table with folding leg, a hinging-locking mechanism as defined in claim 1, characterized in that the said side of said box and the said adjacent locking hinge-plate include complementary bracing means, adapted to engage one with the other in the said locking position.
